CLAIM

The ornamental design for a sandbox, as shown and described.

DESCRIPTION

FIG. 1 is a top view of the sandbox showing my new design; FIG. 2 is a perspective view thereof;

FIG. 3 is a perspective view of a second embodiment of the sandbox as disclosed in FIG. 1;

FIG. 4 is an enlarged perspective view of a third embodiment of a segment of the sandbox as disclosed in FIG. 1; FIG. 5 is a side elevational view of FIG. 1; the undisclosed sides being identical; and,

FIG. 6 is a bottom plan view of FIG. 1.

The undisclosed side of the second and third embodiment are identical to those disclosed in the first embodiment.
